DESIGN FOR A JACKET

Zelma Golden, New York, N. Y.

Application July 23, 1946, Serial No. 131,844

Term of patent 3½ years

(Cl. D3—4)

To all whom it may concern:

Be it known that I, Zelma Golden, a citizen of the United States, residing in New York city, in the county of New York and State of New York, have invented a new, original, and ornamental Design for a Jacket, of which the following is a specification, reference being had to the accompanying drawing, forming part thereof.

Fig. 1 is a front view of the jacket showing my design,

Fig. 2 is the rear view of the jacket shown in Fig. 1, and

Fig. 3 is a fragmentary front view of the jacket shown in Fig. 1, showing one of the pocket flaps in raised position.

I claim:

The ornamental design for a jacket, substantially as shown.

ZELMA GOLDEN.
